(57) **CLAIM**

I claim the ornamental design for a cover for a book or similar article, as shown and described.

DESCRIPTION

FIG. 1 is a perspective view for a cover for a book or similar article showing the first embodiment of my new design; and including a binder strap and a bookmark;

FIG. 2 is a front side elevational view thereof;

FIG. 3 is a rear side elevational view thereof;

FIG. 4 a left side elevational view thereof;

FIG. 5 is a right side elevational view thereof;

FIG. 6 is a top plan view thereof;

FIG. 7 is a bottom plan view thereof;

FIG. 8 is a perspective view of the cover for a book or similar article illustrating it in an open position thereof;

FIG. 9 is an elevational view of a cover for a book or similar article illustrating it in another open position thereof;

FIG. 10 is a perspective view for a cover for a book or similar article showing a second embodiment of my new design; and including a binder strap;

FIG. 11 is a front side elevational view thereof;

FIG. 12 is a rear side elevational view thereof;

FIG. 13 a left side elevational view thereof;

FIG. 14 is a right side elevational view thereof;

FIG. 15 is a top plan view thereof;

FIG. 16 is a bottom plan view thereof;

FIG. 17 is a perspective view of the cover for a book or similar article illustrating it in an open position thereof; and,

FIG. 18 is an elevational view of a cover for a book or similar article illustrating it in another open position thereof.

Broken lines in the drawings are for environmental purposes only and form no part of the claimed design.
